UNITED STATES PATENT OFFICE.

WALTER HAHNEMANN, OF KIEL, GERMANY.

WIRELESS SIGNALING APPARATUS.

1,197,366.

Specification of Letters Patent.

Patented Sept. 5, 1916.

Continuation of application filed February 10, 1913, Serial No. 747,372. This application filed June 11, 1914. Serial No. 844,532.

To all whom it may concern:

Be it known that I, WALTER HAHNEMANN, a subject of the King of Saxony, and residing at Kiel, Germany, have invented a certain new and Improved Wireless Signaling Apparatus, of which the following is a specification.

My invention relates to wireless signaling apparatus and particularly to apparatus for 10 signaling to or from vessels with metallic hulls, being a continuation of Serial No. 747,372.

Arrangements have heretofore been proposed in which metal plates have been sunk 15 in the ground or in the water as electrodes through which electric energy, in the form of direct or alternating current, has been led to the conducting medium (viz. water or earth) for the purpose of transmitting signals to a great distance without the use of 20 metallic conductors. In the arrangements employed to effect this end, it is possible that the electrodes have sometimes been arranged at different depths in the transmitting 25 medium. But investigation of the operation of these arrangements discloses at once that induced current is employed, as is evident from the form, size and arrangement of the electrodes. While it is possible 30 that in some instances the action of current flux might have been used for the production of the signals, such operation appears never to have been previously practised and perhaps its availability for the purpose was 35 not even recognized.

Under normal conditions, if it is desired to signal by means of simple current flux, the proper form of energy for this purpose is the direct current. Its use however is 40 barred by practical difficulties if large bodies of metal are near the electrodes, as for instance in sea signaling, where the electrodes may be carried by a ship having a metal hull. In such cases, where direct 45 current is employed, the ship's hull so effectively short circuits the current that practically no lines of force would remain for the transmission of signals to a distance. By the use of alternating current and raising 50 the frequency of the latter to a high pitch, this short-circuiting can be in large part avoided. This frequency cannot however be raised to an unlimited extent, since the conductivity of sea water makes the transmission 55 of currents of very high frequency im-

possible. Within the limits imposed by these conditions a medium frequency must be selected, and this for iron ships of ordinary size, appears to be a frequency of about five thousand per second.

Now in order to attain with the energy thus sent out a current flux action which is not operative only in a certain direction, the arrangement of the electrodes with respect to each other must be properly determined. 65 An arrangement of these in a horizontal plane, which would of course be the simplest arrangement for a ship, cannot be employed for this would result in the energy emanations being operative only in certain 70 directions.

According to the present invention the desired end is attained by arranging the electrodes vertically one above the other, as a result of which not only is the transmission of the signal only in certain direction avoided, but also the short circuiting action of the ship is eliminated. The energy emanations are strongest in the transverse plane that crosses at the middle point of the 75 imaginary line that connects the electrodes and as a consequence the lines of current flux are transmitted on all sides evenly through the medium while the ship's hull lies in a separate zone in which it does not 80 cause any detrimental effects by short circuiting action, etc.

The electrodes employed to carry out the invention, are metal plates of good electrical conductivity, of which one, (the upper) is 85 secured to the bottom of the ship's hull, while the other is arranged at some distance below the keel, when the ship is floating in a normal depth. Instead of fastening a plate on the ship's hull to form the upper electrode, the hull itself may be used as the upper electrode. Furthermore, the upper electrode may be secured well up on the side of the hull, although of course below the water line; in this case two plates must be 90 employed, one on each side of the ship, and electrically connected together so that they are of the same potential. By placing this electrode higher on the hull, it is obviously 95 possible to lift the lower electrode nearer to the hull of the ship. But care must be taken to have as much water as possible, that is not occupied by the ship's hull or a part of it, between the electrodes of different potential. In an arrangement of this character 100

the hull is in large part interposed between the electrodes, but the consequent tendency to short circuit can be prevented by the use of a current of the highest frequency permissible under the limitations above mentioned. If the upper electrode *i* is arranged on the lower portion of the ship's hull, it becomes possible to employ even direct current for the transmission of the signals.

10 The lower electrode may be suspended by any suitable appliance at the desired depth over the side of the ship. It is however more desirable, in order to maintain as nearly as possible a fixed distance between the electrodes and a constant direction of the imaginary line connecting them, which latter would be altered by the water currents washing against the suspended plate, to mount the lower electrode on a strong, rigid support insulated from the hull. It is advantageous to so arrange it that the electrode and its appliances are protrudable through the hull of the ship, since this makes it possible to readily inspect, repair or adjust the electrode as may be necessary.

15 In the accompanying drawing Figures 1 and 2 are more or less diagrammatic transverse sections through a ship's hull showing my invention applied thereto in two different forms.

20 In the form shown in Fig. 1, the upper electrode *b* is arranged on but insulated from the keel *a*. The coöperating lower electrode *c* is suspended by a suitable suspender *d* passing over rollers *f* to a drum *k*, from all of which it is insulated by the non-conducting connections *e*. The operation of the drum *k* serves to lift or lower the electrode *c* at will. The sending current is transmitted to the electrodes from the source *g* through conductors *h* and *i*, while, when receiving, the transmitted current is led from the electrodes in like manner to a suitable detecting apparatus adjacent *g*.

25 In the form shown in Fig. 2, the upper electrode comprises the two plates *b'*, *b'*, fastened to the ship's hull but insulated therefrom by sheets of non-conducting material *l'*, *l'*. These plates are connected together and to the transmission and receiving apparatus (as in Fig. 1) by the conductors *h'*, *h'*. The coöperating lower electrode *c'* is arranged so as to be protrudable through the hull of the ship and to this end it is fixed to a rigid rod *m* that is surrounded by an insulating sheath *n* and provided with a piston-like head *e* which works in the tube *p* through which the electrode

may be lifted or lowered as may be desired. A slide valve *q* may be provided to close the lower end of the tube *p* after the electrode *c'* has been drawn in.

I claim:

1. A signaling device for a ship comprising two conducting bodies fixed to the ship's hull above the keel, an adjustable electrode below the imaginary line connecting the two said conducting bodies and a current source having its one pole connected to the two conducting bodies and its other pole connected to the electrode. 60

10 2. A signaling device for a ship comprising two conducting bodies fixed to the ship's hull above the keel, an adjustable electrode arranged approximately vertically below the imaginary line connecting the two said conducting bodies and a current source having its one pole connected to the two conducting bodies and its other pole connected to the electrode. 70

15 3. In a signaling device for ships with metallic hulls and for transmitting messages by current flux action, a current source, electrodes connected to said source, one of the said electrodes having means associated therewith for protruding the same through the ship's hull to lie below the other electrode so that a current flux may pass unchecked beneath the hull of the ship. 80

20 4. A signaling device for a ship comprising two conducting bodies fixed to the ship's hull above the keel, an electrode below the imaginary line connecting the two conducting bodies, a rigid rod carrying the said electrode and adjustably protrudable through the hull of the ship to the desired distance from said imaginary line, and a current source having its one pole connected to the two conducting bodies, and its other pole connected to the protrudable electrode. 90

25 5. In a signaling device for ships with metallic hulls and for transmitting signals by current flux action, a current source, a pair of electrodes carried by, but insulated from, the ship and connected to said current source, said electrodes when in use being spaced apart to lie in different horizontal planes so that a current flux may pass unchecked beneath the hull of the ship, and guide means on the ship for securing the lower electrode beneath the ship in predetermined position with relation to the upper electrode. 105

30 In testimony whereof I have signed my name to this specification.

WALTER HAJNEMANN.
